(57) **CLAIM**

The ornamental design for a cap with opening means, as shown and described.

DESCRIPTION

FIG. 1 is a perspective view of a cap with opening means.
FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view of the cap with opening means.

FIG. 7 is a bottom plan view thereof; and,

FIG. 8 is a perspective view of the cap with opening means illustrating the cap opened.
The broken lines shown in the drawings represent a pattern of stitching.
